QIL PUMP

Filed April 24, 1923

Inventor
ORIAN F. DEVOLLO

Ch. Parker
Attorney

UNITED STATES PATENT OFFICE.

ORIAN F. DEVOLLD, OF BARTLESVILLE, OKLAHOMA.

OIL PUMP.

Application filed April 24, 1923. Serial No. 634,360.

To all whom it may concern:

Be it known that I, ORIAN F. DEVOLLD, a citizen of the United States, residing at Bartlesville, in the county of Washington and State of Oklahoma, have invented certain new and useful Improvements in Oil Pumps, of which the following is a specification.

This invention relates to oil pumps and 10 more particularly to a pump having a single actuating piston and a pair of opposed valves operated on the upstroke and down-stroke respectively of the piston to deliver oil upwardly through the casing.

15 An object of the invention is the provision of a pump consisting of a casing, barrel, piston and a pair of valves below the piston to control the flow of oil from the well to the casing.

20 A further object is to provide means for separating sand and other foreign matter from the oil.

25 A further object is the provision of means for preventing the formation of a vacuum behind the piston on its down-stroke.

In the accompanying drawings, I have shown one embodiment of the invention. In this showing:

30 Figure 1 is a central vertical sectional view through a well casing showing the invention applied,

Figure 2 is a horizontal sectional view on line 2—2 of Figure 1,

35 Figure 3 is a view similar to Figure 1 at right angles thereto,

Figure 4 is a horizontal sectional view on line 4—4 of Figure 1,

Figure 5 is a similar view on line 5—5 of Figure 1, and,

40 Figure 6 is a horizontal sectional view through the valve casing on line 6—6 of Figure 1.

Referring to the drawings, the reference numeral 1 designates a well casing of ordinary construction. A casting 2 is secured to the lower end of the well casing. As shown, this casting consists of an annular member having an upper flange 3, which is internally threaded, and adapted to be secured to the lower section of the well casing. The lower portion of the casting is provided with external threads 4, adapted to engage internal threads formed on the upper end of a tubular member 5, forming the outer casing of the pump. The lower end of this tubular member is internally screw-

threaded and is adapted to be secured to a valve member 6. The valve member 6 is provided with a central bore 7, the diameter of which is decreased at its lower end, forming an inclined shoulder 8. A pipe 9 is arranged in the lower end of the bore and extends into the oil in the bottom the well. A cage 10 is arranged in the lower part of the bore 7, resting upon the shoulder 8. This cage is provided with packing 11 to frictionally engage the inner wall of the bore and retain it in position. The upper end of the cage is threaded to receive a substantially similar cage 12. This cage is retained in position by similar packing 13. A valve seat 14 is arranged between the two cages and is adapted to receive a ball valve 15. The cage 12 is threaded to receive a similar member 16 which is retained in position by means of packing 17. A valve seat 18 is arranged between the members 12 and 16 and receives a ball valve 19. These cage members are provided with central bores forming a passage 20 which is controlled by the valves 15 and 19. The upper end of this passage is closed by an upper member 21 which is provided with internal screw-threads to receive the threads formed on the upper end of the member 16. This upper member 21 is provided with a threaded socket 22 which is adapted to receive a rod (not shown) by means of which the entire valve mechanism may be removed from the bore 7.

45 A working barrel 23 is threaded into the upper end of the bore 7 and arranged within the outer casing 5. This barrel is adapted to receive a piston 24 which is provided with suitable packing 25. The upper end of the barrel is received in a ring 26 forming a part of the casting 2 and secured to the outer ring by means of webs 27. A second ring 28 is carried by the webs and is adapted to receive a tubular member 29, slightly greater in diameter than the diameter of the working barrel and arranged within the well casing. The piston is connected to a plunger rod 30 by means of a casting 31 and this plunger rod extends upwardly through the casing in the usual manner. It passes through a guide 32, supported by a ring 33, secured in the upper end of the tubular member 29. A suitable packing gland 34 is carried by the guide and surrounds the plunger rod. Spacing lugs 35 are carried by the guide and adapted to engage the inner wall

of the well casing. The tubular member 29 is provided with openings 36 adjacent its upper end to permit passage of oil from the space between the tubular member and the 5 casing to the interior of the tubular member. The lower end of the tubular member, received in the ring 28, is spaced from the top of the working barrel to provide openings 37.

Above the lower valve 15, there are provided 10 a pair of ports or passages 38, extending through the lower member 6 and communicating with the bottom of the working barrel. Similar ports or passages 39 are arranged between the central passage 20 and the bottom of the casing 5. As shown, these 15 passages are arranged at right angles to the passages 38. An annular member 40, substantially U-shaped in cross section, is arranged on the top of the passage 39, within 20 the chamber 41 formed by the working barrel and the casing 5. As shown, this member is provided with openings 42 in its side walls and is loosely held in position on 25 the top of the passages 39 by screws 43.

In operation, the upward movement of the piston lifts the lower valve 15 from its seat, permitting oil to flow through the pipe 9, passage 20, passages 38 to the working barrel. On the down-stroke of the piston, the 30 pressure forces the valve 15 to its seat. The pressure of oil back through the passages 38 and 20 lifts the upper valve 19 and permits the oil to flow through the passages 39 and the openings 42 of the member 40 35 to the space 41. The pressure of oil causes this member 40 to be raised and lowered on the screws 43 and separates sand and other foreign matter from the oil. The openings 42 permit the oil to pass outwardly into the 40 chamber 41 in a substantially horizontal direction, separating the sand from the oil by the deflection of the oil from its original path of travel. These openings, however, 45 are not essential as the provision of means for raising the member 40 from its seat would cause the separation of the sand from the oil if a solid U-shaped member were employed in place of the construction 50 shown. The oil passes upwardly through the spaces between the webs 27 of the casting 2 and thence through the outer casing

to the top of the well. By providing the openings 36 and the passages 37 oil is permitted to flow into the interior of the tubular member 29 and the formation of a vacuum behind the piston on its downward stroke is thus prevented.

It is to be understood that the form of the invention herewith shown and described is to be taken as a preferred example of the 60 same, and that various changes in the shape, size, and arrangement of parts may be resorted to without departing from the spirit of the invention or the scope of the 65 subjoined claims.

Having thus described my invention, I claim:

1. In an oil pump, an outer casing, a working barrel arranged in said casing, a piston mounted in said working barrel, a member 70 secured to the lower end of said casing; said member being provided with a central passage reduced in size adjacent its lower end forming an inclined shoulder, a valve cage 75 resting on said shoulder, a valve seat mounted on the top of said cage, a ball valve 80 adapted to engage said seat, a second cage secured to said first cage and surrounding the said ball valve, a valve seat mounted on the top of said second cage, an upper ball valve 85 adapted to engage said seat, a cage secured to the upper end of said second cage and surrounding said upper ball valve, and a member secured to the upper end of said last mentioned cage and closing the upper 90 95 end of said central passage, said pump being provided with a passage extending from a point between said valve seats to said foreign matter from the oil. The openings 42 permit the oil to pass outwardly into the working barrel and being further provided with a second passage extending from a point above said upper ball valve to said outer casing.

2. A device constructed in accordance with claim 1 wherein the member closing the outer end of said central passage is provided with a threaded opening for the reception of a tool whereby said cages and said valves may be removed as a unit.

In testimony whereof, I affix my signature.

ORIAN F. DEVOLLD.
